ATTORNEY.

UNITED STATES PATENT OFFICE.

FRANK C. SKILES, OF CHICAGO, ILLINOIS.

DESIGN FOR A LOOSE-LEAF BOOK.

59,606.

Specification for Design.

Patented Nov. 8, 1921.

Application filed September 26, 1919. Serial No. 326,689. Term of patent 7 years.

To all whom it may concern:

Be it known that I, FRANK C. SKILES, a citizen of the United States of America, residing at Chicago, in the county of Cook and State of Illinois, have invented a new, original, and ornamental Design for a Loose-Leaf Book, of which the following is a specification, reference being had to

the accompanying drawing, forming part thereof.

The figure is a perspective view of the book closed.

I claim:

The ornamental design for a loose leaf book, as shown.

FRANK C. SKILES.
